Specification for Design.

Patented Feb. 21, 1922.

Application filed July 7, 1921. Serial No. 483,059. Term of patent 7 years.

To all whom it may concern:

Be it known that I, SAMUEL ANHOUSE, a citizen of the United States, residing at the borough and county of Bronx, city and State of New York, having invented a new, original, and ornamental Design for Fancy Boxes, of which the following is a specification, reference being had to the accompanying drawings, forming part thereof.

Figs. 1 and 2, are isometrical views of opposite sides of a fancy box, showing my new design.

I claim:

The ornamental design for a fancy box, as shown.

SAMUEL ANHOUSE.
